UNITED STATES PATENT OFFICE.

RUTH E. FULTON, OF PERRY, OKLAHOMA TERRITORY.

DOOR-STOP.

SPECIFICATION forming part of Letters Patent No. 659,021, dated October 2, 1900.

Application filed September 21, 1899. Serial No. 731,152. (No model.)

To all whom it may concern:

Be it known that I, RUTH E. FULTON, a citizen of the United States, residing at Perry, in the county of Noble and Territory of Oklahoma, have invented certain new and useful Improvements in Door-Stops, of which the following is a specification.

The object of my invention is to combine simplicity with efficiency and convenience in operation, of which the following is a specification, reference being had to the accompanying drawings, forming a part thereof, in which—

Figure I is a front elevation of my door-stop as attached to a door. Fig. II is a sectional side view on line $\alpha\alpha$ of Fig. I. Figs. III and IV are perspective views.

Similar letters refer to similar parts throughout the views.

In the carrying of my invention into practice I employ a pyramid-shaped body-plate a , through which screws may be passed to secure said plate a to the door. Against the plate a is a reciprocating bolt b , provided with a circular collar g of the same diameter as a bolt-reciprocating wheel c , the latter having on its inner face and near its outer edge a projecting annular rim h , that is placed in and operates in the collar g on the bolt b . Said wheel c is pivoted eccentrically by means of a screw d , being passed through an opening e in the wheel c and an opening f in the body-plate a , near the summit of the latter, and then into the door. The collar g is retained on the annular rim h by a guide-lug i and also by the collar g , being between the body-plate a and a flange j , forming the outer edge of the wheel c . By revolving the wheel c the bolt b may be reciprocated up and down through

an opening k in a guide-loop at the middle of the base of the body-plate a . Said bolt b has a half-round body, with its lower end flat and smooth, so when the required amount of friction is brought to bear against the floor or other surface it will not mar or scratch the latter. The bolt-reciprocating wheel c is provided with a convenient operating-crank l , which is placed between two stop-lugs m and n , provided on the front of the collar g , adapted to limit the movement of the wheel c in reciprocating the bolt b . The door is retained open or partially open by the pressure of the lower end of the bolt b against the floor. Said bolt b is reciprocated down by operating the crank l around to the right or up by operating the crank l around to the left.

Having thus described my invention, what I claim is—

The combination in a door-stop, having a pyramid-shaped body-plate with a guide-loop at its base, a reciprocating bolt passing through an opening in said loop, a circular collar on the bolt, engaged by an annular rim on the bolt-reciprocating wheel the latter pivoted eccentrically by a screw in an opening, near the summit of the body-plate; an operating-crank on the wheel placed between two stop-lugs on the front of the collar, adapted to limit the movement of the wheel in reciprocating the bolt, substantially as described and for the purpose specified.

RUTH E. FULTON.
